P. RASMUSSEN.
MULTIPLE GUIDE ROW STACKED CAKE RECEIVING AND ASSEMBLING MACHINE.
APPLICATION FILED AUG. 30, 1920.

Patented Nov. 22, 1921.

UNITED STATES PATENT OFFICE.

PETER RASMUSSEN, OF DENVER, COLORADO, ASSIGNOR OF ONE-HALF TO STEPHEN KNIGHT, OF DENVER, COLORADO.

MULTIPLE-GUIDE-ROW STACKED-CAKE RECEIVING AND ASSEMBLING MACHINE.

1,397,656.

Specification of Letters Patent.

Patented Nov. 22, 1921.

Application filed August 30, 1920. Serial No. 406,929.

To all whom it may concern:

Be it known that I, PETER RASMUSSEN, a citizen of the United States of America, residing at the city and county of Denver and State of Colorado, have invented new and useful Multiple-Guide-Row Stacked-Cake Receiving and Assembling Machines, of which the following is a specification.

My invention relates to a multiple guide row stacked-cake receiving and assembling machine, and the objects of my invention are:

First. To provide a machine that will receive cakes in stacked form and will confine them in separate rows and convey them where they can be easily and quickly removed from the machine in edgewise stacked groups and placed in shipping boxes.

Second. To provide a stacked-cake receiving machine having a plurality of adjustably widening or narrowing stacked cake guides, adapted to receive between them cakes of different sizes, and

Third. To provide a stacked cake receiving machine that is provided with an upwardly inclined, vertically adjustable and counterbalanced endless belt that is hinged to the horizontal portion of said conveyer.

Fourth. To provide a complete and thoroughly practical multiple guide row stacked-cake receiving and assembling machine.

I attain these objects by the mechanism illustrated in the accompanying drawings, in which—

Figure 1 is a side elevation of the improved machine.

Fig. 2 is a transverse sectional view thereof, on the line 2—2 of Fig. 1.

Fig. 3 is a side view of a portion of the forward end of the machine, the near leg being omitted for clearer illustration.

Fig. 4 is a plan view of a portion of the forward end of the machine, showing the plate for bridging the gap between the conveyer drum and the end of the conveyer supporting table.

Fig. 5 is a plan view of the mechanism for raising and lowering the conveyer drum and the inclined board which supports the forward portion of the conveyer, and

Fig. 6 is a fragmentary plan view show-

ing the manner of hinging one end of the inclined conveyer-supporting table.

Similar letters of reference refer to similar parts throughout the several views. 55

Referring to the drawings:

The numeral 1, designates the supporting frame of my cake row receiving and assembling machine. 2, designates its cake receiving end, and 3, its cake discharging end. 60

At the opposite corner posts 4, of the lower end of the frame, I rotatively mount in bearings 5, vertical rods 6, the lower end portions of which are threaded, and on these rods I threadedly mount yoke-shaped boxes 7, in which a shaft 8, is journaled that extends across the end of the machine and on which a drum 9, is secured, on which is mounted one end of an endless canvas belt 10, the opposite end of which is mounted on a roller 11, that is secured on a shaft 12, that is journaled in sliding boxes 13, that are mounted in a slideway 13^A, and the boxes 13, are adjusted to tighten the conveyer belt by hand screws 13^B, which pass through the ends of the slideways and through the blocks in the usual manner. 70

The bearings 5, are formed on metal bars 5^A, which are secured to the posts 4, and the upper ends of the threaded rods 6, have rigidly mounted thereon, bevel gears 6^A, which mesh with bevel pinions 6^B, on a rod 6^C, which is journaled in bearing 6^D, also formed on the upper ends of the bars 5^A. 80 One end of the rod 6^C, is provided with an operating hand wheel 6^E, by which the rod with its pinions 6^B, is rotated, and the gear 6^A, and rods 6, are thereby turned, by which the boxes 7, are raised or lowered, with the drum 9, which is mounted in said boxes. 85 The upper part of the conveyer is supported at its angular turn by a roller 13^C, and an inclined board underneath it, which will be presently described, and the lower part of the conveyer belt is supported on a roller 13^D, which is mounted on the frame as shown in Figure 1. 90

One end of the shaft 8, is provided with sprocket wheels 14, of different diameters, any one of which is adapted to be connected by a chain to a similar sprocket wheel on a driven shaft—not shown—of the cake de- 100

livering part of a complete cake stacking machine, such as is illustrated in my issued Patent Number 1,217,345 dated February 27, 1917, and also in my pending application, 5 Serial No. 406,928 filed August 30th, 1920.

My present invention relates to improvements in the rear or cake row, assembling part of the machine, and is an improvement on my issued patent, including the improvements made in this rear end part to date.

Upon the side rails 17, that are secured to the corner end posts of the supporting frame of my present machine, are secured brackets 18, which support transverse rods 19, upon 15 which are slidably mounted depending supports 20, the lower ends of which are secured to guide bars 21, which are slightly above the surface of the canvas conveyer belt 10. The guide bars extend over the length of the 20 conveyer 10, and each is made up of an inclined portion 22, and a horizontal portion 23, answering to the corresponding portions of the conveyer 10, and the parts are hinged together at the point 24, where the inclined 25 portion of the belt merges into the horizontal portion, as will appear by reference to Fig. 1.

The forward ends of the inclined portions of the guides 21, however, are supported by 30 standards 25, which are secured to supports on the forward end of an inclined board 26, that forms a supporting table portion for the endless belt conveyer; slotted straps 27, are secured to the side edges of this board 35 26, and bolts 15 extend through the slots of the straps, and into the boxes 7, which arrangement causes the conveyer supporting board to be lowered or raised with the boxes 7, and the drum 9, and the lower end of the 40 conveyer 10, so that the hinged members of the guides will move simultaneously with the inclined portion of the belt when the drum 9 is raised or lowered.

The guide bars 21, are preferably in the 45 form of angle bars, and by sliding the supports laterally on the rods 19, the space between the guide bars 21, may be varied to suit the diameter of the cakes passing over the machine, so that the cakes are maintained in a uniform column of unvarying 50 width during their progress toward the discharge end of the conveyer 10. The guide bars are held at the desired position of adjustment by thumb screws 28, in threaded 55 apertures in the supports 20, which are screwed against the rods 19, and thus hold the supports, with their rails, in the position desired. A horizontal board 29, is also placed under the horizontal portion of the 60 conveyer.

I preferably illustrate three sets of stacked cake confining guide bars in my present improved machine, as my present machine is adapted to be connected to the discharging 65 ends of the cake stacking chutes illustrated

in my pending application, Serial No. 406,930 filed August 30, 1920.

Inasmuch as the lower end of the conveyer, with its three sets of cake guiding bars and its roller and shaft and the lower 70 end of the belt supporting board are too heavy to move upwardly easily when the hand wheel is turned to rotate the threaded rods that are threaded to the conveyer shaft supporting boxes, I provide the opposite 75 sides of the frame and the conveyer with a counter-weight mechanism that is preferably constructed as follows:

To the side rails of the frame I mount 80 rope sheaves 30, on a short shaft or bolt 31, which is secured to the side rails, and extend a rope 32, over it, one end of which is secured to the inclined conveyer belt supporting board 26, and the other end of the rope is secured to a weight 33, which is heavy 85 enough to permit the lower end of the conveyer to be raised easily by the hand wheel and cross-shaft that raises the shaft-supporting boxes of the lower end of the conveyer.

After the belt 10, has been placed on the machine and tightened sufficiently, by adjusting the boxes 13, which support the roller 11, further means are employed for taking up the slack of the belt, when the 95 drum 9, and board 26, are raised or lowered, and thus maintaining a uniform tension of the belt.

The means employed consists of a metal roller 34, having trunnions 35, which are 100 supported in yoke-shaped brackets 36, which are secured to the under edges of the side bars 17, about midway of the length of the horizontal table 29. This roller rests upon the under lap of the belt 10, as shown in Fig. 1, and maintains a uniform tension of the belt, at all times, as the inclination of the board 26, is changed, to meet requirements arising from the different characters of 105 goods which are run over the belt.

That half of the machine having the stationary horizontal belt supporting table 29, is the part from which the cakes are taken and placed in boxes by attendants, who stand on opposite sides of the machine. To 110 the side bars 17, on opposite sides of this part of the machine, are hinged side boards 37, which are held in horizontal positions by arms 38, which are hinged at one end to the outer edge portions of the side boards, and 115 their inner ends are bent at a suitable angle, and are provided with slots 39, which open through the said ends of the arms.

The middle and rear legs 40, of the machine are provided with headed bolts 41, 125 which receive the slotted ends of the arms, and thus support the side boards in horizontal positions. These side boards support the cake receiving boxes, and may also receive the cakes, which are afterward placed in 130

boxes. When the machine is not running, the side boards may be dropped to vertical positions, as shown by dotted lines, Fig. 2, so as to be out of the way, and this is accomplished by simply disconnecting the slotted ends of the arms 38, from the bolts 41.

It will be apparent that when the hinged board 26 is raised to approach a horizontal position, its free end will lie close to the 10 face of the drum 9, and when the board is lowered, its free end recedes from the face of the drum, thus leaving a gap or space between the drum and the end of the board. It is necessary to bridge this gap for the 15 following reasons: Cakes are supplied to this end of the belt 10, by a plurality of stack-forming chutes 42, which are described in my co-pending applications above referred to, and the discharge ends of these 20 chutes rest upon that part of the conveyer 10, beneath which the gap occurs, and this part of the conveyer is supported from beneath, in the following manner:

A rod 43, extends across the front end 25 of the machine, and its ends are supported on the boxes 7. A thin metal plate 44, of the width of the conveyer, is secured at one end upon the said rod by forming a roll upon the end of the plate and passing 30 the rod through the said roll. The plate extends over onto the free end of the board 26, and between the board and the conveyer, thus bridging the gap between the drum and the end of the board, and supporting the 35 conveyer, where the chutes rest.

In operation this machine receives cakes that have been stacked into rows in the stacking chutes of that part of a complete cake stacking machine that is positioned 40 ahead of my present machine and that is positioned to discharge its stacked cakes between the adjustable guide bars of my present machine, and the endless conveyer belt conveys them in these rows in which they 45 are discharged, in overlapping relation to each other, between its guide rails, as these three sets of guide rails are positioned to stand in alinement with the discharge ends of the chutes, a fragmentary view of which 50 is shown operatively connected to the lower cake receiving end of my present cake assembling and removing machine, which conveys them in continuous stacked groups between their guide bars on top of the horizontal portion of the machines, whose operators standing on opposite sides of the machine, scoop each group of stacked cakes 55 as it is conveyed in front of them, into edge-wise stacked rows, and lift them from the guides and machine and place them in shipping boxes.

The object of raising or lowering the lower end of the endless inclined stacked-cake-receiving machine is that some sizes 60 and kinds of cakes retain the overlapping

stacked form in which they leave the discharging ends of the stacking chutes at a less or a greater inclined angle than others. Consequently the adjusting of the lower end of the inclined portion of the stacked cake 70 receiving machine gives the proper gravity pitch to the cakes, and is an essential feature in keeping the cakes in their best stacked form, so that they can be more quickly removed by the cake removing operators, and 75 thus facilitate the handling of large quantities of cakes in their steady, uninterrupted movement through a complete cake stacking machine, of which my present stacked-cake receiving portion is a very essential part, 80 and my invention contemplates its adaptation to any of the cake stacking machines in use, and especially cooperatively connected to and forming a part of the cake receiving and dividing head end machine and also of 85 the cake stacking chutes machine illustrated in my two pending applications herein mentioned.

My invention provides a simple practical machine for handling large quantities of 90 cakes in stacked form so they can be readily removed by attendants and placed instantly in rows in shipping boxes, and while I have illustrated and described the preferred construction and arrangement of my machine, 95 I do not wish to be limited to it as changes may be made without departing from the spirit of my invention.

Having described my invention, what I claim as new and desire to secure by Letters 100 Patent is:

1. A multiple guide row stacked cake receiving and assembling machine, comprising a supporting frame and an endless, traveling, stacked cake conveying belt mounted 105 therein, having an upwardly inclined portion, and a horizontal portion; means for raising or lowering the inclined portion and for counterbalancing the weight of said inclined portion; said inclined portion of said endless, traveling belt being pivotally connected to said horizontal portion; said endless, traveling, stacked cake conveying belt being provided with a plurality of independently adjustable cake guideways. 115

2. A multiple guide row stacked cake receiving and assembling machine, comprising a supporting frame and an endless, traveling, stacked cake conveying belt mounted 120 therein, having an upwardly inclined portion, and a horizontal portion; means for raising or lowering the inclined portion and for counterbalancing the weight of said inclined portion; said inclined portion of said endless, traveling belt being pivotally connected to said horizontal portion; said endless, traveling, stacked cake conveying belt being provided with a plurality of independently adjustable cake guideways; and 125 means including screw-actuated sliding

boxes for supporting one end of said endless cake conveyer, and for tightening the same.

3. A multiple guide row stacked cake receiving and assembling machine, comprising a supporting frame and an endless, traveling, stacked cake conveying belt mounted therein, having an upwardly inclined portion, and a horizontal portion; means for raising or lowering the inclined portion and for counterbalancing the weight of said inclined portion; said inclined portion of said endless, traveling belt being pivotally connected to said horizontal portion; said endless, traveling, stacked cake conveying belt being provided with a plurality of independently adjustable cake guideways; and means including screw-actuated sliding boxes for supporting one end of said endless cake conveyer, and for tightening the same; and means including flat board members for supporting the under side of said inclined and horizontal portions of said conveyer.

4. In a multiple guide row stacked-cake receiving and assembling machine, the combination of the supporting frame, the inclined and horizontally positioned endless traveling conveyer, means for imparting a traveling movement to said conveyer, the board members under the upper part of said conveyer for supporting the same in a flat, traveling position, with the means including gearing and the vertically positioned threaded rods and the counterbalancing weight for raising and lowering the lower end of the inclined portion of said conveyer, a hinged board for supporting the upper lap of the said inclined portion of the conveyer and adjustable therewith; and the plurality of laterally adjustable stacked-cake guideways on the surface of both inclined and horizontal portions of said conveyers, the portions of said guideways on the upwardly inclined portion of said conveyer being arranged to be raised or lowered with said conveyer, the screw actuated boxes for supporting and adjusting the tension of said conveyer, and with the lower end of said conveyer being arranged and adapted to be connected to the discharging ends of cake stacking chutes.

5. In a machine of the character described, the combination with a frame, a table supported therein, comprising a fixed horizontal portion, and a hinged inclined portion, journal boxes on one end of said frame and means for raising and lowering the same, a drum supported in said boxes, means connecting the free end of said inclined table with said boxes, a roller at the opposite end of said frame, an endless conveyer extending around said drum and said roller and supported by said table, means for automatically maintaining the tension of the belt 65 when the drum is raised or lowered, pairs

of laterally adjustable parallel guides extending over the upper lap of said conveyer and supports for the same, each guide having a hinge joint at a point above the hinged end of the inclined member of the table, and a counter balance connected to the free end of said latter member, and means for delivering articles upon the inclined portion of said conveyer between said guides.

6. In a machine of the character described, a frame, an inclined table extending from the front end of the frame and hinged at its inner end in said frame, a horizontal table extending from the hinged end of the inclined table to the other end of the frame, threaded vertical rods supported in bearings on the front end of the frame, journal boxes threaded to said rods, and means for turning said rods thereby to raise or lower said boxes, slotted arms secured to the free end of said inclined table, and bolts extending through said slots and connecting said slotted arms loosely with said boxes, whereby the free end of the said table is raised or lowered with said boxes, a drum supported in said boxes, an adjustable roller in the opposite end of said frame, an endless conveyer extending around said drum and said roller and supported by said tables, a roller for supporting the under lap of said belt, a relatively heavy roller which rests upon the lower lap of said belt, yoke shaped brackets on said frame for supporting the ends of said roller, means for supplying material to the vertically adjustable end of the conveyer, and means whereby said drum may be connected with an operating source.

7. In a machine of the character described, a frame, journal boxes on the front end of the frame, and means for raising and lowering the same, an inclined table hinged at its inner end midway of the length of the frame, and a horizontal table extending thence to the opposite end of the frame, means for connecting the free end of the inclined table with said boxes whereby said end is raised and lowered with said boxes, a drum supported in said boxes in proximity to the said end of the table, the space between the drum and the end of the table being increased or diminished as the inclination of the table is changed; a roller in the opposite end of the frame, an endless conveyer extending around said drum and roller, and supported by said tables, means, beneath the conveyer for bridging the space between the drum and the end of the inclined table, chutes for delivering material to said conveyer, the discharge ends of which rest on said conveyer above said bridging means, and sprocket wheels on the drum shaft, whereby power may be applied to said drum.

8. A frame, journal boxes on the front end of the frame and means for raising and

lowering them, a drum mounted in said boxes, an inclined table, extending from a point adjacent the drum, and hinged at its inner end in said table, a horizontal table 5 extending from the hinged end of the inclined table to the opposite end of the frame, a roller in the latter end of the frame, arms connecting the free end of the inclined table with said boxes, whereby the table is raised 10 or lowered with said boxes, a rod resting on said boxes, a plate secured to said rod and overlapping the adjacent end of the table, an endless conveyer extending around said drum and roller and supported by said

tables, chutes for delivering material to the 15 adjustable end of said belt, their discharge ends resting on said conveyer above said plate, means for automatically maintaining the tension of the belt, when the boxes are raised or lowered, and sprockets on said 20 drum shaft, by which said drum may be connected with driving means.

In testimony whereof I affix my signature in presence of two witnesses.

PETER RASMUSSEN.
